OIL BURNER ELECTRODE GAUGE

William G. Rowell, Quincy, Mass.

Application May 9, 1951, Serial No. 225,318

7 Claims. (Cl. 33—180)

1

This invention relates to a gauge which may be used in setting the electrodes of an oil burner.

As is well known in the oil burner industry, the so-called gun type oil burner has a nozzle thereon which is designed to spray the oil into the fire box in a generally conical form. The angularity of the cone of oil varies with different nozzles, according to the requirements of different fire boxes. In general, however, the included angle of the cone of oil will run from 30° to 90°.

It is also well understood in the oil burner industry that the electrodes providing the spark gap by which the burner is ignited should preferably be located in a particular relation to the cone of oil. In general, this position is close to the cone but not actually in the oil spray. If the electrodes are in the oil, the spark may not jump the gap and there will not be ignition. On the other hand, even if the burner should ignite properly under such conditions, the electrodes will in time become carbonized and may become short circuited. Conversely, the electrodes must not be located so far away out of the oil spray that they will be out of range of an ignitable mixture.

It is customary in this field for oil burner nozzles to be removed periodically and cleaned. In so doing, the electrodes are also removed and their position with respect to the nozzle must be re-established when the nozzle is repositioned in the burner. The problem of accurately locating the electrodes with respect to the nozzle is a difficult one and heretofore has generally been carried out solely under the judgment of the serviceman. No means or equipment of inexpensive accurate character has been available to assist him in the proper positioning of the electrodes in relation to the particular nozzle being serviced.

Accordingly, the principal object of this invention is to provide a gauge which the serviceman or installer may carry with him which may be applied to all types and sizes of conventional gun type nozzles and which when so applied will determine at once the proper position of the electrodes for use with the nozzle in question. The gauge will also indicate the proper lateral spacing of the electrodes so that a spark of correct intensity will be produced when the automatic controls call for initiating operation of the burner.

The invention also includes structure which will make it possible to use the gauge on the conventional nozzle having a hexagonal base regardless of the angular position of the hexagonal portion.

These and other objects of the invention will become more apparent as the description pro-

2

ceeds with the aid of the accompanying drawings in which

Fig. 1 is a plan view of an oil burner nozzle to which the gauge has been applied and showing the electrodes in proper position.

Fig. 2 is a side elevation of Fig. 1.

Fig. 3 is an enlarged side elevation of the gauge alone with the nozzle socket portion in section.

Fig. 4 is a section on the line 4—4 of Fig. 3.

Referring to Fig. 1, the pipe 2 is that running from the oil burner pump into the fire box. The outline of the conventional surrounding tubular housing through which the air from the blower passes on its way to mix with the oil that is ejected from the nozzle is indicated at 4.

The nozzle structure comprises a threaded nut 6 screwed on the end of pipe 2. This nut has a cylindrical extension 8 on the threaded end of which is screwed a conventional spray nozzle 10 shown in dotted lines in Figs. 1, 2 and 3 and in section in Fig. 4. Nozzle 10 comes in a variety of interchangeable sizes with the size of the aperture 11 therein controlling both the volume of oil that may be sprayed into the fire box and the angle of the cone of sprayed oil emitted therefrom. The hexagonal nut portion of the nozzle is of uniform size regardless of the nozzle aperture.

The gauge constituting the present invention comprises a nozzle socket member 12 having a cylindrical interior 14 large enough to fit easily over the hexagonal portion 16 of the nozzle. A spring pressed ball 18 is located in a hole 20 in extension 22 which ball is prevented from escape by an inner lip 24. The ball, however, projects inwardly far enough to engage a face of the nozzle 10. Since in tightening nozzle 10 on extension 8 the hexagonal faces of the nozzle will stop at unpredictable angular positions, the socket member when applied to the nozzle will assume a position related to the particular position of the hexagonal faces. Obviously the nozzle will not present in each instance a horizontal face as shown in Fig. 4 against which ball 18 may rest in centered position. Accordingly it becomes essential to provide means for rotation between the socket member 12 and the extending gauge plate. To provide this arrangement the following construction is used.

At the right hand end of nozzle socket 12 is a hole 26 axially aligned with the hole 14 in nozzle 10. Through hole 26 extends a screw 28 having a head 30. The threaded end of the screw 28 is in corresponding threaded engagement with an

enlarged portion 32 of gauge plate 34. That portion of the screw 28 that passes through hole 26 is not in threaded engagement and is free to turn therein. Thus gauge plate 34 and the affixed screw 28 may be rotated with respect to nozzle socket 12 with the head 30 turning within the nozzle socket. Ease of rotation is facilitated by the inclusion of a washer 36.

On the gauge plate are a group of marks which appear as a plurality of spaced parallel lines the lower six of which have been marked in Figs. 2 and 3 as 0, $\frac{1}{8}$, $\frac{1}{4}$, $\frac{3}{8}$, $\frac{1}{2}$ and $\frac{5}{8}$. These lines and the markings thereon indicate that they are each one eighth of an inch apart. Thus, the unmarked top line above the $\frac{5}{8}$ inch line will be the $\frac{3}{4}$ inch line or, in other words, $\frac{3}{4}$ of an inch from the line marked 0. The 0 line is in horizontal alignment with the center line of screw 28 and the aperture 11 through nozzle 10 but is laterally disposed with respect to the axis of the nozzle by a distance equal to $\frac{1}{2}$ the thickness of gauge plate 34.

Gauge plate 34 also carries a second group of lines which radiate at different angles. These lines cross the previously referred to parallel lines and are marked 30° , 45° , 60° , 70° , 80° and 90° . It will be noted that if all of these angular lines were projected to the left they would converge at the nozzle orifice 11. Since the thickness of screw head 30 limits the longitudinal movement of the gauge to the left and the head 30 abuts against the end of nozzle 10, the angular lines just referred to may be readily marked on the gauge plate 34 to converge at the nozzle orifice 11 regardless of the particular nozzle in use. The reverse side of gauge plate 34 may be similarly marked for convenience but markings on one side will suffice.

From the foregoing, it will be understood that the nozzle socket 12 may be placed over any nozzle and the screw head 30 will come into engagement with the outer end of the nozzle orifice. The depth of nozzle socket 12 is short enough so that its edge will not engage the smooth larger dimension of the cylindrical portion 8. If the gauge is installed while the electrodes are in position, the gauge plate 34 will assume the position shown in Figs. 1 and 2. If the burner has been operating properly and the electrodes are in their correct position with respect to the nozzle, the point of engagement of the electrodes with the marked face of the gauge plate may be quickly and readily noted. For example, in Fig. 2 it will be seen that the electrode engages the plate at the horizontal line marked $\frac{1}{2}$ and along the sloping line marked 30. This means that the point of engagement of the electrode is at a distance $\frac{1}{2}$ inch above the axis of the nozzle orifice and along a line running upwardly at 15° from the horizontal. This indicates that the included angle of the conical spray is 30° , and this angle should be found stamped on the particular nozzle then in use. If the operator then disassembles the nozzle for cleaning purposes, he may, upon re-assembly, position the gauge on the nozzle and then bring the electrodes back to their original positions at which location the burner had previously functioned properly.

If on inspection of the nozzle, the marking thereon should indicate a 45° nozzle instead of a 30° nozzle, and it was desired that the electrodes should be positioned adjacent the 45° cone spray then the ends of electrodes 38 and 40 would be located at the positions where the $\frac{1}{2}$ inch horizontal line crosses the 45° line. The electrodes

when thus repositioned may then be securely clamped to remain thereafter fixed in relation to the nozzle orifice. When the positioning of the electrodes has been completed, the nozzle socket may then be slid off the nozzle with the gauge plate sliding between the electrodes.

The thickness of the gauge plate is equal to the preferred distance the ends of the electrodes should be spaced for producing the best spark. Thus, when the electrodes have been properly positioned and anchored the points will be in exactly the right position with respect to the cone of oil and will be spaced properly to produce a spark capable of igniting the oil spray.

In installing electrodes initially the gauge can be used in substantially the same way. First, the serviceman reads the markings on the nozzle which will indicate the angle of the cone of the oil spray. This tells him at once along which of the angle lines the electrode points must be placed. He may then set the electrodes any place along this line with complete assurance that the spark will be close enough to the oil spray to ignite it but still be outside the area which might produce carbonization of the electrodes.

The markings on the gauge plate are preferably stamped or cast therein for long life and good visibility. The impressions of the markings are not severe enough to affect the spacing of the electrode points.

It is my intention to cover all changes and modifications of the example of the invention herein chosen for purposes of the disclosure which do not constitute departures from the spirit and scope of the invention.

I claim:

1. An oil burner electrode gauge comprising a nozzle socket adapted to fit over an oil burner nozzle having an orifice therethrough, a member within said socket in axial alignment with the orifice of said nozzle and adapted to limit the movement of said nozzle into said socket, a gauge plate pivoted to said nozzle socket on an axis aligned with said nozzle orifice axis when said nozzle is positioned in said socket whereby regardless of the angular position of said socket with respect to said nozzle said gauge plate may be rotated to vertical position, and markings on at least one face of said gauge plate for assisting in determining the location of the points of the oil burner igniting electrodes with respect to said orifice, said markings comprising a plurality of parallel lines, all parallel to the said nozzle orifice axis and a plurality of converging lines crossing said parallel lines, said converging lines directed to converge substantially at said nozzle orifice when said nozzle is positioned in said socket.

2. An oil burner electrode gauge as set forth in claim 1, the thickness of said gauge plate being approximately equal to the normal spacing of electrode points for proper operation in igniting the oil emitted from said nozzle.

3. An oil burner electrode gauge comprising a socket member adapted to be positioned over an oil burner nozzle having an orifice, means for releasably securing said socket to said nozzle, a gauge plate rotatably mounted on said socket with the axis of rotation in axial alignment with said orifice when said socket has been positioned on said nozzle, means for limiting the distance said nozzle may be introduced into said socket whereby the horizontal distance from the exit of said orifice to said gauge plate will be constant regardless of the particular nozzle on which said

socket may be placed, and markings on at least one face of said gauge plate for assisting in determining the location of the points of the oil burner igniting electrodes with respect to said orifice, said markings comprising a plurality of parallel lines, all parallel to the said nozzle orifice axis and a plurality of converging lines crossing said parallel lines, said converging lines directed to converge substantially at said nozzle orifice when said nozzle is positioned in said socket.

4. An oil burner electrode gauge comprising a nozzle socket adapted to fit closely over the hexagonal nut portion of a conventional oil burner nozzle having an orifice, means within said socket for engaging said nozzle and limiting the distance said nozzle may be moved into said socket, said means comprising a screw threaded member extending through the end of said socket with the head thereof within said socket, a gauge plate having an enlarged portion at one end thereof into which said screw threaded member is secured, said gauge plate rotatable with respect to said nozzle socket along an axis in alignment with said orifice axis when said nozzle socket is positioned on said nozzle, the thickness of said gauge plate being equal to the proper spacing between the points of igniting electrodes, said gauge plate having markings on at least one face thereof for assisting in determining the location of the electrode points with respect to said nozzle orifice, said markings comprising a plurality of parallel lines, all parallel to the said nozzle orifice axis and a plurality of converging lines crossing said parallel lines, said converging lines directed to converge substantially at said nozzle orifice when said nozzle is positioned in said socket.

10

5. An oil burner electrode gauge comprising a socket member adapted to fit closely over an oil burner nozzle having an orifice, said socket member provided with means positioned within the socket for locating said socket relative to said nozzle and with means for holding said socket fixed with respect to said nozzle, a gauge plate pivotally attached to said member for rotation about an axis aligned with the axis of said orifice whereby said plate can be brought to position between said electrodes regardless of the angular position of said member on said nozzle, said gauge plate having markings thereon for determining the position of the ends of the electrodes used to ignite the oil emitted from said orifice.

6. An oil burner electrode gauge as set forth in claim 5, some of the markings on said gauge plate being non parallel and sloping in the same general direction to converge at or close to the point where said nozzle orifice would be when said member is mounted on a nozzle.

7. An oil burner electrode gauge as set forth in claim 5, some of the markings on said gauge plate being non parallel and sloping in the same general direction to converge at a point in a plane perpendicular to the axis of the said orifice and in a plane including said axis and at right angles to said gauge plate when said gauge is in position on said nozzle.
